41

Fig. 2.

UNITED STATES PATENT OFFICE.

GEORGE H. MERWIN, OF MILFORD, CONNECTICUT.

ROTARY COIN BOARD.

Application filed August 2, 1924. Serial No. 729,804.

To all whom it may concern:

Be it known that I, GEORGE H. MERWIN, a citizen of the United States, residing at Milford, county of New Haven, State of Connecticut, have invented a new and useful Rotary Coin Board, of which the following is a specification.

This invention relates to coin boards for the use of cashiers in the booths of stores, 10 concessions, and the like, to prevent misappropriation of funds collected. Concessionaires at beaches, summer resorts, and the like, have found it especially difficult to secure honest help to operate their concessions, 15 this help being mostly transient and usually care to stay only for a short time in a position, and get all they can out of it while they are there. Where they are trusted with a sum of money to make change and the 20 change collected is placed in this fund, it is a simple matter to misappropriate a large share of the funds collected as the concessionaire in a great many cases has no means of checking up on these collections.

It is, therefore, an object of this invention 25 to provide a simple and inexpensive device to prevent these misappropriations of funds and to insure the concessionaire or proprietor receives the funds collected by his 30 employee. In the drawings I have shown a device constructed according to my invention adapted especially for use by concessionaires at resorts and the like as above mentioned, but the principles of the invention 35 are by no means limited to such use, as by a similar construction on a smaller scale it is equally adapted for use by cashiers in stores, subway booths and so forth.

With the foregoing and other objects in 40 view, I have devised the construction illustrated in the accompanying drawing forming a part of this specification, similar reference characters being employed throughout the various figures to indicate corresponding elements. In this drawing,

Fig. 1 is a rear elevation of a table or booth front showing my improved coin board applied thereto, a portion of the table and one of the boards being broken away to 45 more clearly show the construction.

Fig. 2 is an end elevation thereof looking from the right of Fig. 1.

Fig. 3 is a top plan view of the construction showing a portion of two connected 50 boards and the means for operating them on an enlarged scale.

Fig. 4 is a transverse section substantially on line 4—4 of Fig. 3, and

Fig. 5 is a transverse section substantially on line 5—5 of Fig. 3. 60

In the drawing the table or counter is shown as comprising a rectangular frame of angle iron 10 and 11 mounted on suitable supporting legs 12, also of angle iron, and along the front and rear of the top are strips 65 or boards 13 providing a substantially rectangular opening 14 in which my improved coin board 15 is mounted. This coin board is shown as being triangular in cross section, that is, it has three plain sides 16 also substantially rectangular to close the opening 14 in the top of the counter, and the board is preferably so mounted that the surfaces of these sides when in the opening are substantially flush with or slightly below the top 70 surface of the counter to give a neat and attractive appearance. Although the drawing shows the board as triangular, having three sides, it obviously may be made of any number of sides desired so long as it has a 75 plurality of these sides arranged to be brought successively into the opening by a step by step rotary movement of the board. In the present case a number of triangular panels 17 and 18 are provided spaced from 80 each other a suitable distance throughout the length of the board to which the side members 16 are attached by any suitable means, such as screws 19. To the end panels are mounted brackets 20 having trunnions 85 to rotate in suitable bearing blocks 21 mounted on suitable cross bars 22 forming a support therefor, and the board is rotated in these bearings to discharge the coins placed 90 on the board through the opening 14 and 95 bringing the sides successively into this opening.

A simple and effective means for giving the required step by step movement and holding the board in proper position is 100 shown in Figs. 3 and 4. On the shaft 23 joining the brackets 20 is keyed a ratchet 24 which in the present instance has a plurality of notches 25 in its periphery equal in number to the number of sides in the board. 105 A second disc 26 is secured to the shaft, as by a set screw 27, and has a plurality of notches 28 in its periphery also equal in number to the number of sides in the board. A catch 29 is pivoted to the frame by means 110 of a bracket 30, and this catch has a lug 31 adapted to extend into the notches 28 and

lock the board in proper position to maintain the sides 16 in the opening 14 and substantially flush with the top of the counter. A block 32 is loosely mounted on the shaft 5 and carries a pawl 33 which is pivoted thereto at 34, and a spring 35 tends to hold the pawl on its pivot to press its free end against the periphery of the ratchet 24, and when in proper position to move this end 10 of the pawl into the notches 25. A hand lever 36 is connected to the block 32 for operating it, and it projects rearwardly from the counter as shown in Figs. 3 and 4 for easy manipulation by the operator. The 15 catch lever 29 carries a laterally extending pin 37 adapted to be engaged by the upper edge of the block 32 so that this block may release the catch. The notches 25 and the ratchet 24 are located substantially as shown 20 in Fig. 4, so that when the lug 31 is in one of the notches 28 the free end of the pawl 33 rests on the periphery of the ratchet slightly below the notch, as shown in full lines.

25 When it is desired to rotate the board to discharge the coin or coins placed thereon and to bring another side into the opening 14, the operator lifts the free end of the lever 36 a short distance, as shown in dotted 30 lines, Fig. 4. Under this movement the upper edge of the block 32 engages the pin 37 and lifts the lug 31 of the catch out of the notch 28 which unlocks the board. At the same time the free end of the pawl 33 engages 35 in the notch 25 and then a quick downward movement of the free end of the lever will rotate the board to allow any coins which may be thereon to drop through the opening 14, and to bring a new face or side of the board into this opening. When 40 this new face or side has reached the proper position the lug 31 of the catch will drop into another notch 28 and lock the board in this new position.

45 Below the board are inclined side walls 38 and inclined end walls 39 to form a chute to conduct coins dropped from the board into a suitable receptacle 40, such as a drawer which may be removed through the 50 rear wall 41 of the counter. This receptacle may be locked by any suitable means, such as a key or combination lock to prevent access thereto except by an authorized party.

55 In operation the cashier is given a certain amount for change. The customer if he has not the proper change secures it from the cashier and places the proper change he is to give the cashier on the top of the board. 60 The cashier then rotates the board as described above by manipulating the lever 36 and the coins are discharged automatically into the locked receptacle 40, the cashier being allowed to handle the cash only in the 65 operation of making change. At the end of

the day the proprietor or other authorized person may unlock the receptacle and remove the entire receipts for the day, and he has a definite means of checking up on the cashier because he knows what amount was given to the cashier at the beginning of the day for the purpose of making change. 70

The drawing shows a multiple board, that is, there are really three boards operated by the same mechanism to accommodate a relatively long counter, and furthermore, the boards may be made of practically any length desired. It will of course be obvious the same construction and arrangement may be employed for single or short boards as 80 is found desirable. 75

Having thus set forth the nature of my invention, what I claim is:

1. In a device of the character described, a substantially flat topped table or counter 85 having an opening in the top thereof, a coin board rotatably mounted in said opening and polygonal in cross section to provide a plurality of faces each adapted to lie in said opening to close the same and arranged for deposit of coins thereon, manual means accessible from the rear of the table or counter to rotate said board to bring the faces successively into said opening and discharge coins on the upper face through the opening, and means to stop movement of the board when the faces reach the opening and retain them therein. 90

2. In a device of the character described, a substantially flat topped table or counter 100 having a substantially rectangular opening in the top thereof, a coin board in said opening and mounted to rotate about a horizontal axis, said coin board being polygonal 105 in cross section with rectangular faces adapted to close said opening and arranged for deposit of coins thereon, and manual means accessible from the rear of the table or counter for rotating said board with a step by step movement to bring the faces successively into said opening and discharge coins on the upper face through the opening. 110

3. In a device of the character described, a substantially flat topped table or counter 115 having an opening in the top thereof, a coin board rotatably mounted in said opening to substantially close the same and having a plurality of faces adapted to lie in said opening to close the same, manual means accessible from the rear of the table or counter for rotating said board to bring the faces successively into said opening and retain them therein, a key controlled compartment below said board, and a chute 120 leading from said opening to the compartment. 125

4. In a device of the character described, a substantially flat topped table or counter having a substantially rectangular opening 130 in the top thereof, a coin board in said open-

ing and mounted to rotate about a horizontal axis, said coin board being polygonal in cross section with rectangular faces adapted to close said opening, manual means accessible from the rear of the table or counter for rotating said board with a step by step movement to bring its faces successively into said opening, a lock controlled receptacle beneath said board, and a chute leading from said opening to the said receptacle.

5. In a device of the character described, a table or counter having an opening in the top thereof, a coin board rotatably mounted in said opening to substantially close the same and having a plurality of faces adapted to lie in said opening, a lever, means operated by movement of the lever in one direction for imparting a step by step rotative movement to the board to bring its 15 faces successively into said opening, means for securing the board with the faces in this position, and means operated by movement of the lever in the opposite direction for releasing said securing means.

20 6. In a device of the character described, a table or counter having a substantially rectangular opening in the top thereof, a coin board in said opening and mounted to rotate about a horizontal axis, said coin board being polygonal in cross section with 25 rectangular faces adapted to close said opening, a lever, means operated by movement of the lever in one direction for imparting a step by step rotative movement to the board to bring its faces successively into said opening, means for securing the board with the faces in this position, and means operated by movement of the lever in the opposite direction for releasing said securing 30 means.

7. In a device of the character described, a table or counter having an opening in the top thereof, a coin board rotatably mounted in said opening to substantially close the same and having a plurality of faces adapted to lie in said opening, a ratchet connected to said board, a pivoted lever, a pawl operated by movement of the lever in one direction to engage the ratchet and rotate the board with a step by step movement, a member secured to said board provided with a plurality of notches, a catch arranged to engage said notches to hold the board with its faces in the opening, and means operated by movement of the lever in the opposite direction to release said catch.

45 8. In a device of the character described, a table or counter having a substantially rectangular opening in the top thereof, a coin board in said opening and mounted to rotate about a horizontal axis, said coin board being polygonal in cross section with rectangular faces adapted to close said opening, a ratchet connected to said board, a pivoted lever, a pawl operated by movement of the lever in one direction to engage the ratchet and rotate the board with a step by step movement to bring its faces successively into said opening, a second ratchet secured to the board and having notches corresponding in number to the faces of the board, a catch pivoted to the table and provided with a lug to seat in said notches and hold the board with one of its faces in said opening, and cooperating means connected to the catch and lever for releasing the catch by movement of the lever in the opposite direction.
